CLAIM

The ornamental design for a projectile launcher and loader, as shown and described.

DESCRIPTION

FIG. 1 is a top, front, left perspective view of first embodiment of a projectile launcher and loader in accordance with our design;

FIG. 2 is a top, rear, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is a top, front, left perspective view of second embodiment of a projectile launcher and loader in accordance with our design;

FIG. 10 is a top, rear, right perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines represent portions of the Projectile launcher and loader in which the design is embodied that form no part of the claimed design.
